MULTIPLE TIMECARD

Grange K. Pattison, Chicago, Ill.

Application December 23, 1950, Serial No. 202,523

2 Claims. (Cl. 282—23)

1

The present invention relates in general to records and recording and has more particular reference to improved means for recording working time intervals, the invention pertaining more especially to an improved multiple sheet time recording pad unit particularly well adapted to facilitate the making and keeping of records of successive work intervals occurring during extended work periods.

Time record cards are commonly issued to individual workers for the purpose of recording the working time intervals of the person to whom the card is issued. Working interval records conventionally are and have been made and kept on "time cards" adapted for marking by action of the card holding worker at the commencement and termination of each work interval, the cards being usually marked by insertion thereof in and operation of time printing mechanism commonly referred to as a "time recording clock." Such time cards usually comprise forms printed on relatively heavy gauge card stock. Time cards are normally individually marked, as with a typewriter, to identify the card with the person to whom the card is issued. Such cards are also normally, if not invariably, arranged to cover several working intervals within a more extended working period, such as one complete work week, after which the cards are collected for auditing, new cards being issued for the next succeeding work period. A considerable amount of secretarial labor thus is required for individually marking and issuing the cards at the commencement of each work period. Furthermore, the cards, being of substantial thickness, present a storage problem if preserved for any length of time after the record making period.

An important object of the present invention is to provide improved time record card means allowing for the issuance thereof to individual workers at minimum expense of secretarial labor required to mark the improved card means, the improved record card means of the present invention serving also to minimize the storage problem encountered in preserving working time records after the same have been made and audited.

Another important object of the invention is to provide an improved time card unit embodying a plurality of padded sheets of relatively thin material supported in stacked relationship on a relatively rigid backing plate, each sheet providing space for the recording of successive working intervals during an extended working period, such as a work week, whereby the unit will cover several successive working periods, as for example

2

thirteen consecutive working weeks, by successively removing the padded sheets each at the termination of a work period, without disturbing the remaining sheets, the several padded sheets according marking areas in superposed registration for the marking of individual data thereon as by means of a typewriter, and each sheet having transfer pigment applied upon the rear surface thereof in registration with said marking areas, whereby all of the padded sheets of a unit may be simultaneously marked.

The foregoing and numerous other important objects and advantages and inherent functions of the invention will become apparent as the same is more clearly understood from the following description which, taken in connection with the accompanying drawings, discloses a preferred embodiment of the invention.

Referring to the drawings,

20 Fig. 1 is a perspective view of a multiple sheet time recording pad unit embodying the present invention;

Fig. 2 is a fragmentary face view of a portion of a sheet of the pad unit shown in Fig. 1;

25 Fig. 3 illustrates the back of the sheet portion shown in Fig. 2;

Fig. 4 is a sectional view taken substantially along the line 4—4 in Fig. 1; and

30 Figs. 5, 6 and 7 are sectional views similar to Fig. 4 showing modified forms of construction.

To illustrate the invention, the drawings show a time record keeping unit 11, in the form of a pad, comprising a plurality of sheets 13 preferably of thin yet relatively tough material, such as paper, the sheets being secured together at or adjacent their opposite ends, and being preferably mounted and secured at said opposite ends upon a backing panel 14 of somewhat heavier material, such as paper board or thin card stock.

In this connection, the sheets may be padded together and secured to the backing panel as by means of cement 16 applied only at the opposite end edge extremities of the sheets and panel, as shown in Fig. 7. The sheets 13 however may be perforated, as along tear lines 15, parallel to and spaced inwardly of one or both of the opposite edges of the sheets. The sheets preferably are thus provided with tear lines at least adjacent the top end of the pad, in which

45 case the sheets and panel at the opposite or bottom end of the unit may be cemented together at the extremities of the bottom end edges thereof, in the manner shown in Fig. 7. As shown in Figs. 1—6, however, sheets may be perforated on 50 tear lines 15 adjacent both ends of the pad unit,

the sheets being padded together and secured to the backing panel 14 between the tear lines 15 and the end edges of the sheet as by means of cement 16 to secure the sheets together and to the backing panel, as indicated in Fig. 4 of the drawings; or the sheets may be fastened together and to the backing panel as by means of staples 17 as shown in Fig. 5. If desired, a strip of binding material 18 may be secured, as by cementing or otherwise, upon the opposite end edges of the pad, said binding strips preferably overlying the backing panel 14 as well as the end edges of the uppermost sheet 13, outwardly of the tear lines 15, as shown more particularly in Fig. 6. These binding strips may serve to strengthen and protect the ends of the pad and facilitate the insertion of the pad in the usually slot-like pocket of time printing mechanism in which the pad unit is adapted to be inserted for time marking purposes.

Each sheet 13 is the substantial duplicate of every other sheet and they are padded in superposed registration. Each sheet comprises a recording area 19 adapted to receive time interval recording markings by operation of a time recording clock in which the unit may be placed for marking. Each sheet also comprises a marking area 20 adapted to be marked, as in a typewriter, with identifying indicia, such as the name, number and working department of the person to whom the card is to be issued, as a part of the card issuing operation. Each sheet also may include an accounting area 21 adapted to be marked with audit information, such as days worked, the work week covered by the sheet, the number of hours worked during the period, the applicable rate of pay, total earned, tax withholding, and like information required in auditing the record sheet.

Each sheet also, on the rear face thereof, in registration with the marking area 20, as shown more particularly in Fig. 3 of the drawings, is provided with a layer or coating of transfer or copying pigment 22, such as carbon black, such layer facing upon and overlying the marking area 20 of the next underlying sheet 13. As a consequence, in preparing a unit 11 for issuance, the name and other personal data of the worker to whom the unit is to be issued may be applied in the marking areas 20 of all of the sheets 13 of the pad simultaneously, merely by typewriting or otherwise printing the information in the marking area of the uppermost sheet 13 of the pad unit, the remaining sheets being marked by the copying action of the layers 22. The marked unit may then be issued and used by the owner thereof during the successive work periods represented by the successive sheets 13 of the pad. At the conclusion of each work period the uppermost sheet may be removed by tearing the same from the pad along the tear lines 13. The time marked uppermost sheet may be delivered for auditing while the person to whom the unit has been issued continues to hold and use the same for time recording purposes during successive working periods. While pads embodying the present invention may, of course, be made up with any desired number of sheets 13, it is thought that pads comprising thirteen sheets, representing a quarter annual period, will provide a convenient unit not only for use in standard time recording mechanism but one which is well adapted to facilitate accounting procedures. It will be appreciated, of course, that considerable saving of card issuing labor will be accomplished where

it is necessary to perform the card issuing function but four times a year instead of fifty-two, as is necessary when using conventional record cards.

- 5 It will be obvious also that the relatively thin paper record sheets 13 can be preserved and stored easily, thereby substantially minimizing the problem of maintaining time records after the same have been audited.
- 10 15 20 25 30 35 40 45 50 55 60 65 70 75
- If desired the back panel 14, which preferably comprises heavier material than the sheets 13, may also be formed with recording, marking and accounting areas duplicating the corresponding areas of the sheets and disposed in the pad in underlying registration with respect to said sheet areas. In such an arrangement the backing card may itself constitute the time recording element covering the concluding work period of the series for which the pad may have been issued. The physical contrast between the relatively heavy back panel and the relatively thinner sheets 13 may be utilized, in accounting procedures, to indicate the termination of an accounting period to accounting and card issuing personnel, and to denote the necessity of issuing a fresh pad unit for the next succeeding accounting period.

In this connection a pad unit comprising thirteen sheets and a suitable backing panel may have overall thickness of the order of $\frac{1}{16}$ inch and hence be well adapted for use in conventional time marking mechanisms for time record purposes, without alteration of existing marking equipment.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the form herein disclosed being the preferred embodiment for the purpose of illustrating the invention.

The invention is hereby claimed as follows:

1. A time recording pad unit adapted for marking in clock controlled printing mechanism for time recording purposes, said pad unit embodying a plurality of sheets, means securing the opposite ends of said sheets together at the opposed margins of the pad, to hold the sheets in stacked relation, each of said sheets having designated areas defined in the front faces thereof and disposed in superposed registration in the pad unit, including a time marking area and an indicia receiving area for receiving pad-identifying indicia, said sheets each having a layer of copying pigment disposed on the backs thereof in underlying registration with the indicia receiving area of the sheet, each sheet being free of copying pigment in registration with its time marking area, whereby all of the sheets may simultaneously be marked with identical identifying indicia, and the sheets may be individually marked for time recording purposes in the time marking area thereof, each of said sheets, after being so individually marked, being successively removable from said pad unit by separating the sheet from the unit along the end margins thereof, to thereby reveal the time marking area of a next underlying sheet in condition for the reception of time record markings thereon.

2. A time recording pad unit adapted for marking in clock controlled printing mechanism for time recording purposes, said pad unit embodying a plurality of sheets of thin, flexible stock

and a backing panel of relatively heavier and less flexible material, means securing the opposite ends of said sheets and panel together at the opposed margins of the pad, to hold the same in stacked relation, each of said sheets having designated areas defined in the front faces thereof and disposed in superposed registration in the pad unit, including a time marking area and an indicia receiving area for receiving pad-identifying indicia, said sheets each having a layer of copying pigment disposed on the backs thereof in underlying registration with respect to the indicia receiving area of the sheet, each sheet being free of copying pigment in registration with its time marking area, whereby all of the sheets and the backing panel may simultaneously be marked with identical identifying indicia and the sheets may be individually marked for time recording purposes in the time marking areas thereof, each of said sheets, after being so indi- 10 15 20

vidually marked, being successively removable from said pad unit by separating the sheet from the pad unit along the end margins thereof, to thereby reveal the time marking area of a next underlying sheet in condition for the reception of time record markings thereon.

GRANGE K. PATTISON.
